(57) **CLAIM**

The ornamental design for a tea infuser, as shown and described.

DESCRIPTION

FIG. 1 is a front perspective view of a tea infuser showing my new design;

FIG. 2 is a side view thereof;

FIG. 3 is the opposite side view of FIG. 2 thereof;

FIG. 4 is a front view thereof;

FIG. 5 is a rear view thereof;

FIG. 6 is a top view thereof;

FIG. 7 is a bottom view thereof; and,

FIG. 8 is a perspective view showing the tea infuser in an open position.

The broken lines in the drawings are included for the purpose of illustration and form no part of the claimed design.
